UNITED STATES PATENT OFFICE.

JOHN G. ROBERTS, OF DOBBS FERRY, NEW YORK, ASSIGNOR TO WESTERN ELECTRIC COMPANY, OF NEW YORK, N. Y., A CORPORATION OF ILLINOIS.

AUTOMATIC SWITCHING MECHANISM.

1,134,230.

Specification of Letters Patent.

Patented Apr. 6, 1915.

Original application filed March 10, 1906, Serial No. 305,272. Divided and this application filed June 12, 1914. Serial No. 844,666.

To all whom it may concern:

Be it known that I, JOHN G. ROBERTS, a citizen of the United States, residing at Dobbs Ferry, in the county of Westchester 5 and State of New York, have invented a certain new and useful Improvement in Automatic Switching Mechanism, of which the following is a full, clear, concise, and exact description.

10 This invention relates to switching mechanism for automatic telephone exchange systems and is a division of the invention described in my copending application, Serial No. 305,272, filed March 10, 1906, in 15 which one of the systems with which this switching mechanism is adapted for use is described and claimed.

The switching mechanism of this invention is of the type in which a large number 20 of stationary or passive terminals are arranged in a bank or banks, and movable contacts called wipers are adapted for movement into engagement with different ones of the stationary or passive terminals. The 25 travel of the movable contacts is effected by means of continuously operating power driven members which are normally out of active engagement with the movable element of the switching mechanism and which 30 are arranged to be brought into active engagement with the movable element of the switching mechanism through electromagnetic clutch mechanism, which may be controlled from a distant point. In accordance 35 with this invention, these power driven contacts or wipers have movement in two different stages; that is, under control of two different electromagnetic clutch devices. One of these devices is adapted to control 40 the movement of the contacts or wipers to bring them into position before particular groups of stationary or passive terminals and the other of the clutch devices is adapted 45 to control the movement of the wipers to bring them into engagement with particular terminals of the group before which the traveling contacts had previously been moved.

This invention particularly relates to 50 switching devices of the above class in which the members of the clutch mechanism are brought into frictional engagement with one another so as to prevent undue strain upon the mechanism when the motion is

initiated, and to the stop mechanism adapted to definitely locate the movable contacts at the end of their first and their second stage movements.

This invention is illustrated in the accompanying drawings in which

Figure 1 is a front view of the switch with part of the structure removed; and Fig. 2 is a side view of the switch with other parts of the structure removed.

The switch comprises a frame consisting 65 of two parallel rods 1 and transverse plates 2, upon which are mounted the movable and stationary switch contact members and the mechanism for operating the former. The movable members 3, 4 and 5 are rigidly secured to a rod 6 from which they are insulated by insulating sleeves 7. Associated with each of the movable members 3, 4 and 5 are a number of stationary or passive terminals 8 which may be arranged in banks 75 of ten rows, fourteen terminals in a row, or in any other grouping which the character of the circuits which are to be controlled requires.

The movable members or brushes are 80 adapted to be brought into contact with any one of the fixed or stationary terminals by movements in two stages; one vertical and the other horizontal, the vertical movement preferably occurring first to bring the movable members opposite a particular row or group of terminals with one of which the connection is to be made, and the horizontal movement occurring thereafter and causing the wipers to sweep over the terminals in 90 that particular row or group until they are brought into connection with a desired terminal in the group.

In accordance with this invention, constantly moving parts are employed which 95 are adapted to be brought into active engagement with a member associated with the rod 6 to effect the vertical and horizontal movements of the wipers carried by this rod. In the present instance the cylinder or 100 drum 9 is carried by and secured to the rod 6 and is adapted to be engaged by two constantly rotating disks 10 and 11. The disk 10 is adapted to be electromagnetically moved into contact with the cylinder or 105 drum 9 to cause the rod 6 with its associated switch members to move vertically, while the disk 11 is adapted to be electromagnetically

moved into contact with the cylinder or drum 9 in order to impart rotation to the rod 6 and thus cause the horizontal movement of its associated contact wipers.

5 The disks 10 and 11 are similarly arranged. Each is fulcrumed in the end of its associated lever 12 and 13 respectively, the disk 10 being in engagement with a constantly rotating disk 14 and the disk 11 being in engagement with a constantly rotating disk 15. These latter disks are carried upon the shafts 17 and 18 and are thereby rotated from any suitable source of power.

15 The levers 12 and 13 are fulcrumed upon and concentric with their associated shafts 17 and 18 and each carries on its end, opposite the end which carries the disk, an armature 20 which is in operative relation with 20 associated electromagnets 21 and 22, which are suitably mounted upon the frame of the switch.

The mechanism controlled by the magnet 21 is mounted so that the disk 10 rotates in a 25 vertical plane just out of contact with the surface of the cylinder or drum 9, and the mechanism controlled by the magnet 22 is so arranged that the disk 11 rotates in a horizontal plane just out of contact with the 30 surface of the cylinder or drum 9. The driving disks 10 and 11 are normally held in their retracted positions.

The rod or shaft 6 is provided with a reTRACTING SPRING 23 which serves first through 35 torsion and then through axial expansion to return the switch members to their normal resting position. In order to prevent the return of the rod 6 as soon as the driving disks 10 and 11 are disengaged from the drum 9, mechanically controlled retaining 40 mechanism is provided, comprising a vertical retaining ratchet 25, a horizontal retaining ratchet 26, and an electromagnet 27, the armature 28 of which cooperates with 45 two pawls 29 and 30, the second of which is adapted to engage the teeth of the horizontal retaining ratchet 26 when the magnet is energized to correctly position the wipers before a row of terminals at the end of the 50 first stage movement, and the first of which is adapted to engage the teeth of the vertical retaining ratchet 25 when the magnet is energized to correctly position the wipers upon particular terminals after the second stage movement. Obviously, the arrangement 55 may be reversed so that the pawls normally engage their respective ratchets and are withdrawn therefrom when the magnet is energized. Upon withdrawal of the 60 pawls 29 and 30 from their respective ratchets, the shaft 6 with its movable switch members returns to normal under the influence of the spring 23, first in its horizontal or rotary movement and then in its 65 vertical movement.

In the operation of the switch, current is first caused to pass through magnet 21, which responds by attracting its armature and bringing disk 10 into contact surface of the cylinder or drum 9. Since the disk 10 70 is constantly rotated, it immediately causes, through its frictional engagement with the surface of the cylinder 9, an upward movement of the cylinder and shaft 6 corresponding in speed to the speed of rotation of 75 the driving mechanism, the amount of movement of the shaft being determined by the length of time the disk 10 is maintained in engagement with the surface of the cylinder. This vertical movement of the shaft 80 places the contact wipers 3, 4 and 5 in position just in front of, but out of engagement with, the contacts of a particular row or group with one of which the connection is desired. Current is now caused to pass 85 through magnet 22 which responds by moving its armature, and its associated rotating disk 11 into contact with the surface of the cylinder or drum 9, thus imparting rotation to the shaft 6 and horizontal movement to its associated brushes. This movement likewise takes place at a rate depending upon the rate of speed of the associated power mechanism. The extent of the movement of the brushes in their horizontal direction depends upon the duration of the electric current through the electromagnet 22. The wipers 3, 4 and 5 will be accurately centered upon a particular set of stationary or passive terminals 8 when the riding disk 100 11 is withdrawn from its engagement with the drum 9 by reason of the fact that the spring 23 will move the shaft 6 slightly in a reverse direction until the pawl 29 comes in contact with a particular tooth on the horizontal retaining ratchet 26, the teeth and pawl being so positioned that when they are in engagement, the set of brushes is properly positioned upon a particular set of contacts. 105

When the current through the retaining magnet 27 is interrupted, the pawls 29 and 30 are withdrawn from the horizontal and vertical retaining ratchets and the shaft 6 with its associated wipers returns to its normal position. 110

Although this invention is illustrated and described with respect to certain specific details of construction, it is to be understood that they may be modified without in any 115 way departing from the spirit or scope of this invention.

What is claimed is:

1. A switch for an automatic telephone exchange, comprising stationary contact members and a movable contact member, said movable contact member being arranged to have a vertical movement and a horizontal movement, constantly moving means associated with said movable member, but 120

- normally out of engagement therewith, for effecting said movements, electromagnetic controlling mechanism for throwing said moving means into engagement with said 5 movable member, and electromagnetically controlled retaining mechanism for maintaining said movable member in the position to which it has been moved.
2. A switch for an automatic telephone exchange, comprising a plurality of stationary contact members, a movable contact member having a horizontal and a vertical movement and having a driven surface connected therewith, a movable arm, a friction driving member carried thereon and adapted to be moved into engagement with said surface to cause the vertical movement of said member, means for causing said driving member to rotate, a magnet arranged to swing said arm to bring said driving member into engagement with said driven surface, and electromagnetically controlled retaining means for holding said movable member in the position to which it is moved.
- 10 3. A switch for an automatic telephone exchange, comprising a plurality of stationary contact members, and a movable contact member having a horizontal and a vertical movement, and having a driven surface associated therewith, constantly operating driving mechanism adapted to be moved into contact with said driven surface to effect the vertical movement of said member, constantly operating driving mechanism adapted to be moved into engagement with said driven surface to effect the horizontal movement of said member, and means adapted to retain the movable member in the position to which it is moved.
- 15 4. A switch for an automatic telephone exchange, comprising a plurality of stationary contact members, a movable contact member having a vertical movement and a horizontal movement and having a driven surface connected therewith, a constantly moving horizontal driving member and a constantly moving vertical driving member normally out of engagement with said driven surface, and electrically actuated mechanism associated with each of said driving members, and adapted to bring either one into engagement with said driven surface to effect a horizontal or a vertical movement of said movable member.
- 20 5. A switch for an automatic telephone exchange, comprising a plurality of stationary contact members, a movable contact member adapted for a vertical movement and a horizontal movement, and having a driven part connected therewith, a constantly operating vertical driving member and a constantly operating horizontal driving member normally out of engagement with said driven part, a lever upon which each of said driving members is mounted, and magnetically actuated means for tilting each of said levers to bring said driving members into engagement with said driven part.
- 25 6. A switch for an automatic telephone exchange, comprising a plurality of cylindrically mounted stationary contact members, a movable member arranged to have a vertical movement and a horizontal movement of rotation, a driven cylinder connected therewith, a driving disk for effecting the vertical movement and a driving disk for effecting the horizontal movement of said driven cylinder and its associated movable switch member, a lever supporting each of said disks, a constantly rotating disk fulcrumed at the axis of each of said levers and in engagement with the associated driving disk, and an electromagnet for each of said levers, adapted to tilt the same to move the associated driving disk into engagement with the driven cylinder.
- 30 7. A switch for an automatic telephone exchange, comprising a plurality of cylindrically mounted stationary contact members, a movable member arranged to have a vertical movement and a horizontal movement of rotation, a driven cylinder connected therewith, a driving disk for effecting the vertical movement and a driving disk for effecting the horizontal movement of said driven cylinder and its associated movable switch member, a lever supporting each of said disks, a constantly rotating disk fulcrumed at the axis of each of said levers and in engagement with the associated driving disk, an electromagnet in operative relation with each of said levers, and adapted to tilt the same to move the associated driving disk into engagement with the driven cylinder, and an electromagnetically controlled retaining mechanism adapted to hold the movable member in the position to which it is moved.
- 35 8. A switch for an automatic telephone exchange, comprising a plurality of cylindrically mounted stationary contact terminals, a movable contact terminal arranged to have a vertical movement and a horizontal movement of rotation, a driven cylinder connected with said movable member, a driving disk normally out of engagement with said cylinder, electromagnetically controlled mechanism for moving said driving disk into engagement with said cylinder for effecting the vertical movement of the cylinder and its associated movable switch member, and means for effecting the horizontal movement of rotation of said cylinder and its associated member.
- 40 9. A switch for an automatic telephone exchange, comprising a plurality of cylindrically mounted stationary contact members, a movable contact member arranged to have a vertical movement and a horizontal

movement of rotation, a driven cylinder connected with said movable member, a driving disk for effecting the vertical movement of the cylinder and its associated movable switch member, a lever upon which said driving disk is supported, a constantly rotating disk fulcrumed at the axis of said lever and having engagement with said driving disk, a magnet in operative relation with 5 said lever and adapted to move the same to swing the driving disk into engagement with the driven cylinder, and means for effecting the horizontal movement of rotation of said cylinder and its associated switch member.

10. A switch for an automatic telephone exchange, comprising a plurality of cylindrically mounted stationary contact members, a movable contact member arranged to have a vertical movement and a horizontal movement of rotation, a driven cylinder connected with said movable member, a driving disk for effecting the vertical movement of the cylinder and its associated movable switch member, a lever upon which said driving disk is supported, a constantly rotating disk fulcrumed at the axis of said lever and having engagement with said driving disk, magnets in operative relation with 15 said lever and adapted to move the same to swing the driving disk into engagement with the driven cylinder, means for effecting the horizontal movement of rotation of said cylinder and its associated switch member, and electromagnetic retaining mechanism for holding the movable member in the position to which it is moved.

11. In a selector, the combination with 20 stationary terminals and brushes arranged to traverse said terminals, of a longitudinally movable support for said brushes, a body having a friction surface carried by said support, a constantly rotating power member, and an electromagnet for causing operative engagement of said power member 25 with the friction surface of said body.

12. In a selector, the combination with 30 stationary terminals, of brushes arranged to engage said terminals, a support for said brushes carrying a friction surface, power members located adjacent said surface, and electromagnets for selectively causing the operative engagement of said surface with any of said power members.

55. 13. In a selector, the combination with rows of stationary terminals and brushes arranged to traverse said rows, of a longitudinally movable rod carrying said brushes and carrying a body having a friction surface, a 60 rotatable friction disk adjacent said means, and an electromagnet for causing operative engagement of said means with said friction disk.

14. In a switching device, the combina-

tion with terminals arranged in groups, of a 65 contact member therefor having movement in two stages, a pair of constantly moving driving members, an electromagnet for causing the operative relation of one of said driving members with said contact member 70 to move it in its first stage, and a second electromagnet for causing the operative relation of the other of said driving members with said contact member to move it in its second stage.

15. In a switching device, the combination with stationary terminals, of a movable contact member, a friction member movable with said contact member, a constantly rotating friction member, and electromagnetic 80 means for bringing said friction members into engagement to move said contact member to a particular set of stationary terminals.

16. In an automatic switch, a group of 85 stationary terminals, a brush, a support for said brush, means for moving said support to cause said brush to traverse said terminals, said means comprising a rotatable power member, a friction disk thereon, a 90 co-operating friction element on said support, and an electromagnet for causing the operative engagement of said friction disk with said co-operating element.

17. In a switching device, the combination 95 with a plurality of groups of terminals, of a contact member adapted for engagement with any of the terminals of said groups, means to move said contact past various groups of terminals, power driven friction 100 mechanism for moving said contact into engagement with particular terminals of a group, and stop mechanism for accurately centering said contacts upon particular terminals when the power driven friction 105 mechanism is inactive.

18. In a switching device, the combination with a plurality of groups of stationary terminals, of a movable contact member adapted for connection with individual terminals 110 of said groups, power driven friction mechanism for moving said contact to particular groups of terminals, stop mechanism to accurately center the movable contact member before a particular group of terminals, and 115 means to move said contact into engagement with particular terminals of the group to which said contact was moved by said power driven friction device.

19. In a switching device, the combination 120 with groups of terminals, of a contact adapted to be moved in two stages, first to pick out a group and then to pick out a particular terminal in the group, power driven friction mechanism for moving said 125 contact in each of its stages, stop mechanism for accurately locating said contact at the end of the first stage movement thereof, and

stop mechanism for accurately locating said contact at the end of the second stage movement thereof.

20. In a switching device, the combination with groups of terminals, of a contact member for engagement with the individual terminals of any group, two separate power driven friction rollers, electromagnetic means for associating one of said friction rollers with said contact device to move the latter to a particular group of terminals, additional electromagnetic means for asso-
- 5

ciating the other of said friction rollers with said contact device to move the latter to a particular terminal in the group, and means 15 to maintain said contact in connection with said particular terminal after the disengagement of said friction rollers.

In witness whereof, I hereunto subscribe my name this 9th day of June A. D., 1914.

JOHN G. ROBERTS.
